[57] CLAIM

The ornamental design for a disk storage holder, as shown and described.

DESCRIPTION

FIG. 1 is a perspective view of the disk storage holder of the instant invention;

FIG. 2 is a top plane view thereof;

FIG. 3 is a front plane view thereof;

FIG. 4 is a right side plane view thereof a left side view not shown forming a mirror image of said right side view; and, FIG. 5 is a rear plane view thereof.

The bottom of the article, not shown in the drawing or described in the specification, forms no part of the claimed design.
